UNITED STATES PATENT OFFICE.

ROBERT JOHN FOSTER, OF MONTREAL, QUEBEC, CANADA, ASSIGNOR
TO MERGENTHALER LINOTYPE COMPANY, A CORPORATION OF
NEW YORK.

KNIFE-WIPER.

No. 832,661.

Specification of Letters Patent.

Patented Oct. 9, 1906.

Application filed May 5, 1906. Serial No. 315,382.

To all whom it may concern:

Be it known that I, ROBERT JOHN FOSTER, of the city of Montreal, Province of Quebec, Dominion of Canada, have invented a new 5 and useful Improvement in Knife-Wipers, of which the following is a specification.

My invention has reference to linotype-machines, wherein slugs or linotypes are cast in a solid mold mounted in a vertical inter- 10 mittingly-rotating wheel, by which a slug is presented in front of an ejector, by which it is delivered edgewise from the mold between two parallel trimming-knives.

In practice it is found that the shavings 15 from the hot slug have a tendency to adhere to the edges of the trimming-knives, so that unless removed they are liable to become attached to the type-faces of the succeeding slugs.

My invention has in view the removal of 20 these shavings from the knives after each shaving or trimming action; and to this end it consists in a yielding spring-supported wiper carried by the mold-supporting wheel 25 in such a manner as to traverse the edges of the knives. I am aware that both reciprocating wipers mounted in the main frame and a brush attached to the mold-wheel have been used for this purpose; but in practice 30 these constructions are found to be open to certain objections, which are overcome by the construction herein shown and claimed.

Referring to the accompanying drawings, Figure 1 represents a face view of the mold- 35 carrying wheel having my knife-wiper attached. Fig. 2 is a cross-section on the line 2 2 of the preceding figure. Fig. 3 is a section through the mold-wheel knives with the wiper in operative position.

In the drawings, A represents the vertical intermittingly-rotating mold-wheel, containing 40 the usual slotted mold B, which stands in a horizontal position during the casting action.

C and C' are two vertical knives fixed to 45 the frame, the space between them being equal to the thickness of the required slug.

D is a horizontal ejector mounted in guides in the main frame directly opposite the space 50 between the knives.

After the casting action the mold-wheel is turned until it presents the mold in a vertical position with the contained slug in front of

the ejector D, which then advances, expelling the slug from the mold and driving it forward between the knives C C' into the receiving-galley, as usual.

E represents my improved wiper, designed to remove the metal chips or shavings from the knives C C'. It consists of a flat sheet of 6c leather, felt, or equivalent material e, secured firmly at one edge in a clip or holder e', having pivots e², mounted in ears on a plate e³, which is screwed or otherwise firmly secured to the face of the mold-wheel A. A spring 65 e⁴, seated at its ends on elevated surfaces on the plate e³, extends behind or beneath the clip e', which is constructed with eccentric surfaces e⁵ to bear thereon. This spring holds the wiper or pad e normally outward in 70 such manner that when the mold-wheel is turned to carry the mold from the ejecting position the wiper will be carried lengthwise over the edges of the knives C C' in such manner as to remove any adhering chips or 75 shavings. The spring admits of the wiper yielding or turning backward and causes it to act with gentle pressure upon the knives and also admits of its yielding and turning backward and downward toward the disk in 80 the event of its encountering any obstruction in the course of its travel. The pivotal yielding action of the wiper compensates for any change in its length due to wear or other causes, and this insures under all circumstances 85 the proper action of the wiper in relation to the knives.

While I prefer to retain the details of construction herein shown, it is understood that the essence of the invention lies in pivoting 90 or otherwise mounting the wiper so that it may yield against the resistance of a spring tending to hold it at any operative position, and it is manifest that the details of the wiper, the clip, and the spring may be widely 95 modified, provided this mode of action is retained.

Having described my invention, what I claim is—

1. In a linotype-machine, and in combination with the slug-trimming knives and the rotary mold-carrying disk, a knife-wiper pivoted to the disk, and a spring tending to hold the wiper outward from the disk.

2. In a linotype-machine and in combination with a mold-carrier and slug-trimming

knives, a knife-wiper secured to the mold-carrier and comprising a base-plate, a wiper of soft material pivoted thereto, and a spring tending to urge the wiper outward toward the knives.

3. A knife-wiping attachment for linotype-machines comprising a base-plate, a clip pivoted thereto and projecting at right angles therefrom, a wiper secured in the clip, and a

spring tending to hold the wiper in its outer position.

In testimony whereof I hereunto set my hand, this 2d day of May, 1906, in the presence of two attesting witnesses.

ROBERT JOHN FOSTER.
